RAIL MEMBER FOR REMOVABLY MOUNTING
SINUOUSLY CORRUGATED WIRE SPRINGSWilliam H. Neely, Cleveland, William C. Sander,
Solon, and Charles E. Smith, Hudson, Ohio, as-
signors to The Universal Wire Spring Com-
pany, Bedford, Ohio, a corporation of Ohio

Application July 21, 1951, Serial No. 237,942

5 Claims. (Cl. 155—179)

1

This invention relates in general to supporting members for springs of spring constructions, and, more particularly to supporting rails for sinuously corrugated wire springs assembled to wire spring constructions.

The primary object of this invention is the provision of a rail member adapted to readily removably and non-shiftably support corrugated wire springs of the type embodying left and right-handed loops connected with each other by cross wires, the rail member including for each spring to be supported two aligned, hook-shaped elements arranged in laterally spaced, reversed relation with respect to each other to seat and grip opposite sides of one of the cross wires of a corrugated wire spring when such cross wire is shifted into engagement with said elements, and a third hook-shaped element positioned in spaced, symmetrical relation with respect to said two elements and constructed to engage and grip one of the cross wires adjacent to the cross wire seated and gripped by the said two aligned hook-shaped elements.

Another object of the invention is the provision of a rail member adapted to readily removably and non-shiftably support sinuously corrugated wire springs embodying left and right-handed loops connected with each other by cross wires, the rail member including, for each spring to be supported, two, aligned, struck-up portions having hook-shaped form and arranged in laterally spaced, reversed relation with respect to each other to effect seating and gripping of opposite sides of one of the cross wires of a corrugated wire spring, when such cross wire is shifted into engagement with said elements, and a third hook-shaped struck-up portion having hook-shaped form and arranged in spaced symmetrical relation with respect to said two struck-up portions, said third struck-up portion adapted to engage and grip one of the cross wires adjacent to the cross wire seated and gripped by the said two struck-up portions.

A further object of the invention is the provision of a rail member as described above in which the two aligned, hook-shaped, struck-up portions which are arranged in laterally spaced, reversed relation with respect to each other include opposed, slanted edge portions to facilitate locking engagement of a corrugated wire spring with the hook-shaped, struck-up portions by rotating the spring while one of its cross members is positioned between the two struck-up portions.

With the above and other incidental objects

in view, the invention has other marked improvements and superiorities which radically distinguish same from presently known structures. These improvements and superior characteristics, embodying certain novel features of construction are clearly set forth in the appended claims and the preferred embodiment of the invention hereinafter shown with reference to the accompanying drawing forming part of the specification.

In the drawing:

Fig. 1 is a plan view of a rail member constructed in accordance with the invention, the rail member having attached thereto single convolutions of sinuously corrugated wire springs;

Fig. 2 is a sectional view on line 2—2 of Fig. 1;

Fig. 3 is a plan view of a rail member similar to Fig. 1 having placed thereon a fragmentarily shown corrugated wire spring in position to engage when rotated a cross wire with the two cooperating struck-up portions of the rail member;

Fig. 4 is a plan view similar to Fig. 3 showing in full line the corrugated wire spring properly mounted on the rail member and in dash-dotted lines the wire spring just before its engagement with the third struck-up portion of the rail member;

Fig. 5 is a sectional view on line 5—5 of Fig. 1; and

Fig. 6 is a sectional view on line 6—6 of Fig. 1.

Referring now more in detail to the exemplified form of the invention shown in the drawing, reference numeral 1 denotes a U-shaped rail member embodying a seating or resting portion 3 having downwardly extended side flanges 4 and 5. Seating or resting portion 3 is formed with a plurality of groups of hook members, each group of which includes two aligned, hook-shaped elements 6 and 7 laterally spaced from each other a short distance and reversed with respect to each other to extend their open ends in opposite directions, and a third hook-shaped element 8 positioned in spaced, symmetrical relation with respect to elements 6 and 7. These latter elements are struck up from seating portion 3 which for such purpose is slit to form oppositely extending tongue members 9 and 10—tongue member 9 being bent upwardly and outwardly and tongue member 10 being bent upwardly and inwardly.

Hook-shaped elements 6 and 7 include upper wall portions 11 and 12, respectively, spaced from the seating surface 14 of seating portion 3 a distance approximately equal to the gage

of the sinuously corrugated wire spring 18 having its cross wire 16 engaged and held by elements 6 and 7.

Hook-shaped element 8 is positioned in spaced, symmetrical relation with respect to hook-shaped elements 6 and 7 and also struck up from seating portion 3 which for this purpose is slit to form a tongue member 17 bent upwardly at an angle of substantially 45 degrees and provides a seat 18 adapted to engage the middle portion 16 of cross wire 20 adjoining the cross member 18 of gripped convolution 21 of sinuously corrugated wire spring 18.

The described hook-shaped elements cooperate as a group in properly removably seating, holding and gripping a sinuously corrugated wire spring on rail member 2 and permit quick and efficient mounting and demounting of such spring. The steps to be taken in mounting spring 18 on rail member 2 are clearly disclosed in Figs. 3 and 4 and these steps, taken in reverse, effect quick and efficient demounting of the spring.

Mounting of a sinuously corrugated wire spring 18 on rail member 2 is effected by placing the spring, as shown in Fig. 3, on the seating surface 14 of seating portion 3 so that cross wire 16 extends between hook-shaped elements 6 and 7, then spring 18 is rotated in a direction indicated by arrow 22 to engage and grip cross wire 16 by wall portions 11 and 12 of elements 6 and 7 and seating surface 14 of seating or resting portion 3 (see the position of cross wire 16 in Fig. 4); finally cross wire 20 is forced into engagement with tongue member 17 by yieldingly bending spring 18 (see dash-dotted line 23) in a direction indicated by arrow 24 to shift said cross wire over tongue member 17 and downwardly and then by releasing spring 18 cross wire 20 is automatically engaged with hook-shaped element 8 when the spring, allowed to snap back, regains its original shape.

Preferably, as shown, hook-shaped elements 6 and 7 have opposing corner edges of their upper wall portions 11 and 12 cut on slanting, parallel lines 25 and 26, respectively, to facilitate locking engagement of these elements with the cross member of a sinuously corrugated wire spring placed on seating portion 3 so that one of the cross wires of the wire spring is positioned between the hook-shaped elements 6 and 7.

Rail members of the type described are particularly well suited for sinuously corrugated wire springs made of wire with gauges ranging from 10 to 14, which wires can readily be handled in the manner described without use of special tools and danger of deformation.

Having thus described our invention, what we claim is:

1. In a rail member for mounting sinuously corrugated wire springs, a metal strip, two aligned, laterally spaced, hook-shaped elements on said strip, said elements including open hook ends and being arranged in inverted relation with respect to each other to extend their open hook ends in opposite directions, and a third hook-shaped element arranged parallel to said

two elements in axially offset relation with respect to these hook-shaped elements for cooperation therewith in removably mounting a sinuously corrugated wire spring on said metal strip.

5 2. In a rail member for mounting sinuously corrugated wire springs, a metal strip, two aligned, laterally spaced, hook-shaped elements formed as struck-up portions of said strip, said elements including open hook ends and being arranged in inverted relation with respect to each other to extend their open hook ends in opposite directions, and a holding element struck up from said strip arranged in axially offset relation with respect to said hook-shaped elements and adapted to cooperate therewith in removably mounting a sinuously corrugated wire spring on said metal strip.

10 3. A rail member for mounting sinuously corrugated wire springs comprising a metal strip, two aligned, hook-shaped elements with open hook ends arranged on said strip in laterally spaced, inverted relation with respect to each other to extend their open hook ends in opposite directions and a third hook-shaped element on said strip, said third element including an open hook end and being arranged in axially spaced relation with respect to said aligned elements and facing such elements with its open hook end.

15 4. A rail member for mounting sinuously corrugated wire springs comprising an elongated metal strip, aligned groups of hook-shaped attachment means arranged on said strip in longitudinally spaced relation, each group including a pair of aligned, laterally-spaced, hook-shaped portions struck up from said strip and shaped to include open hook ends, each pair having its hook-shaped portions arranged in inverted position with respect to each other to extend the open hook ends of each pair in opposite directions, and a third hook-shaped portion struck up from said strip and including an open hook end, the third hook-shaped portions of each pair facing with their open hook ends the struck-up portions of such pairs and being axially spaced with respect to such struck-up portions.

20 5. A rail member as described in claim 4, wherein the inverted, laterally spaced, two hook-shaped portions of each group include upper wall portions having bias-cut edge portions, and wherein the bias-cut edge portions of such upper wall portions extend parallel to each other to facilitate a releasable mounting of sinuously corrugated wire springs on the aligned groups of the hook-shaped attachment means of the rail member.
